U.S. Cl. D83—1

FIG.2

FIG.1

FIG.3

FIG.4

FIG. 5

FIG. 6

FIG. 7

FIG. 8

FIG. 1 is a side perspective view of an enclosure for self-contained underwater breathing apparatus incorporating the design,

FIG. 2 is a side elevational view thereof,

FIG. 3 is a rear elevational view thereof,

FIG. 4 is a front elevational view thereof,

FIG. 5 is a top end view looking from the top side toward the bottom side,

FIG. 6 is a bottom end view looking from the bottom side toward the top side,

FIG. 7 is a side elevation of a modified embodiment of the breathing apparatus disclosed in FIG. 1, wherein the only difference resides in the forward half of the enclosure which is shaded to show a contrasting color; and

FIG. 8 is a rear elevation of a further modified embodiment of the breathing apparatus disclosed in FIG. 1, wherein the only difference resides in the omission of the holes from the rear portion of a housing.

I claim:

The ornamental design for an enclosure for self-contained underwater breathing apparatus, as shown and described.
